ELEMIR J. NEY, OF LOWELL, MASSACHUSETTS,

ASSIGNOR TO THE LOWELL MANUFACTURING COMPANY.

Letters Patent for a Design No. 100, dated August 13, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other Fabrics, of which the following is a full, clear, and exact description, reference being had to the accompanying drawings making part of this specification.

Corner A is one-fourth of a figure composed of cross-shaped blocks, the spaces between which are occupied by small lines.

B, in the centre, is a branch supporting a rose, with leaves and buds. Corner C is one-fourth of a rosette, from which extends the feather work 1. The frame D and the mottled band E extend throughout the design, crossing each other at various points, and, by their connections, surround figs. A and B and the feather work 1.

Fig. 2 is an irregular lined figure underlying a section of the frame D. The grounds 3 and 4 are formed of small regular work.

The colors employed for the different portions of the design may be varied to suit the taste and wish of the manufacturer.

Claim.

What I claim as my invention, and desire to secure by Letters Patent, is—
The design for carpets or other fabrics herein set forth.

E. J. NEY.
